DESIGN FOR A HAND MIRROR OR SIMILAR ARTICLE

Max H. Storch, Bell Harbor, N. Y.

Application November 3, 1936, Serial No. 65,665

Term of patent 3½ years

To all whom it may concern:

Be it known that I, Max H. Storch, a citizen of the United States and resident of Bell Harbor, Long Island, in the county of Queens and State of New York, have invented a new, original, and ornamental Design for a Hand Mirror or Similar Article, of which the following is a specification, reference being had to the accompanying drawing, forming a part thereof. Fig. 1 is a plan view, and Fig. 2 is a side view of the hand mirror or similar article showing my new design.

The dominant features of my design reside in the portions shown in full lines.

I claim:

The ornamental design for a hand mirror or similar article substantially as shown and described.

MAX H. STORCH.
